UNITED STATES PATENT OFFICE.

WILLIAM U. GRIFFITHS, OF PHILADELPHIA, PENNSYLVANIA.

MEANS FOR ACTUATING FLUSH-TANK VALVES.

Application filed March 24, 1926. Serial No. 96,927.

My invention relates to means for opening or controlling the valves of flush tanks for water closet apparatus.

The general object of the invention is to provide means of the character indicated which not only is novel in construction but which is extremely simple and of a character such that it is not likely to get out of order after it has been installed.

In order that the invention may be readily understood and its practical advantages fully appreciated reference may be had to the accompanying drawing in which I have illustrated one form of a convenient mechanical embodiment of the invention. However, it will be understood that the invention is susceptible of embodiment in other forms of construction than that shown and that changes in the details of construction may be made within the scope of the claims without departing from the invention.

In the drawing:

Fig. 1 is a view in side elevation of a flush tank for water closet apparatus provided with the invention, the means embodying the invention being shown in dash lines and a portion of a side of the tank being broken away for the purpose of showing the valve structure the valve of which is to be opened and closed;

Fig. 2 is a view in elevation looking from the inside of the tank toward the rear side of the valve operating means;

Fig. 3 is a vertical sectional view taken on the line 3—3 of Fig. 2; and

Fig. 4 is a horizontal sectional view taken on the line 4—4 of Fig. 1.

Referring to the drawing: 1 designates a flush tank having an outlet at 2 which is adapted to be closed by a ball valve having a stem 4 which is guided in a sleeve 5 at the outer end of an arm 6 supported upon an overflow pipe 7 of usual construction. The upper end of the stem 4 is provided with an enlargement or eye 9 by means of which a connecting link 10 is prevented from becoming disengaged from the said stem. The upper end of the said connecting link is connected to the outer end portion of an arm 11 which extends rearwardly from a shaft 12 mounted in bearings 13 at the lower end of a depending arm 14. The arm 11 is provided with a plurality of openings 15 into which the upper end of the connecting link 10 may be inserted in order to vary the distance of the point of connection from the

axis of rotation of the shaft 12. The shaft 12 may be adjusted longitudinally within the bearings 13.

The arm 14 is provided at its upper end with an enlargement 16 having a forwardly extending hollow projection or boss 17 which is polygonal in cross section. The said boss projects into an opening 18 in the side 19 of the tank 1 which is of corresponding polygonal shape. The outer end of the opening 18 is concealed by a knob 20 having a central opening 21 extending therethrough. The inner end portion of the said opening is of less diameter than the remaining portion thereof whereby shoulders are formed at 22. A bushing 25 extends through the inner portion of the opening 21 of smaller diameter and also through the opening 18 as well as through the opening through the upper end portion 16 of the arms 14. The outer end of the said bushing is provided with a flanged head, as indicated at 26, which is adapted to contact with the shoulder 22. The inner end of the bushing 25 is screw threaded for engagement with a nut 27 by means of which the arm 14 is adapted to be clamped against the inner surface of the side 19 while the knob 20 is adapted to be clamped upon the outer surface of the said side in opposing relation to the portion 16 of the arms 14. The shoulders 22 of the knob 20 and the wall 19 are clamped between the flanged head 26 upon the bushing 25 and nut 27.

A reciprocable or linearly movable rod 30 is slidably mounted within the bushing 25. To the outer end of the said rod a finger piece or knob 31 is secured. The inner portion of the said knob is of a size to fit loosely within the opening 21. The outer portion of the said knob is enlarged so as to form a shoulder 32 which is adapted to be seated normally against the outer end of the knob 20. The inner end portion of the rod 30 extends through a slot 35 adjacent the upper end of an upwardly extending arm 36 having a head portion 37 at its lower end provided with an opening 38 through which the shaft 12 extends. The said head is located or positioned between the spaced arms 14, as is clearly shown in the drawing. The arm 36 is secured to the shaft 12 by means of a split pin 40 which extends through an opening extending transversely of the head 37 and through any one of the openings 41 through the shaft 12. By removing the

split pin 40 the shaft 12 may be adjusted longitudinally through the bearings 13. The rear or inner end portion of the rod 30 is retained in engagement with the slot 35 by means of a washer 43 and a pin 44, the washer being located between the upper end portion of the arm 36 and the said pin and the latter operating to retain the washer in place. Normally, when the valve 3 is in closed position, the arms 11 and 36 occupy the positions shown in full lines in Fig. 3 of the drawing. When it is desired to operate the said arms to effect opening movement of the valve 3 the knob 31 is pulled outwardly to cause a like outward movement of the rod 30. Such outward movement causes a like movement of the arm 36 to a position as indicated in dash and dot lines in Fig. 3 of the drawing and simultaneously causes pivotal movement of the shaft 12 so that the arm 11 rigidly connected therewith is moved into the position also indicated in dash and dot lines in said Fig. 3. It will be noted that the arm 11 moves upwardly thereby transmitting through the connecting link 10 a lifting force to the valve 3 to cause upward movement thereof into open position. Upon release of the knob 31 upon the emptying or discharge of the water from the tank 1 so as to permit descending movement of the valve 3, the combined weight of the latter, the connecting link 10 and of the arm 11 is sufficient to cause rotatable movement of the shaft 12 and of the arm 36 toward the rear. By reason of the contact of the upper end portion of the arm 36 with the washer 43 the rod 30 together with the knob 31 are moved inwardly so that they are returned to the position shown in full lines in Fig. 3 of the drawing.

It will be seen that by my invention I have provided a simple construction comprising a minimum number of parts constructed and combined in such manner that the likelihood of breakage is reduced to a minimum, and wherein the valve operating means is not likely to get out of order after having been installed.

Having thus described my invention, what I claim and desire to secure by Letters Patent is:

1. In means for actuating a flush tank valve, the combination of a rotatable shaft having an inwardly extending arm and also having an upwardly extending arm, the latter being provided with an opening therethrough adjacent its upper end, means for connecting the first named arm to the valve to be actuated, a bearing for the said shaft mounted upon a side of the said tank, and a reciprocating rod extending through and supported by the said side of the tank and having its inner end extended through and slidably engaged with the opening in the second named arm, substantially as described.

2. In means for actuating a flush tank valve, the combination of a flush tank, a shaft bearing mounted upon the inner side of a wall of said tank, a shaft mounted in said bearing, said shaft having an inwardly extending arm, connections between the said arm and the valve to be actuated, and the said shaft also being provided with an upwardly and inwardly extending arm which is provided with an opening adjacent its upper end, a rod slidably mounted within an opening through the said side of the tank, said rod extending through the opening in the last mentioned arm, means for retaining the said rod in engagement with the said opening, and means whereby the said rod may be reciprocated to effect rotation of the said shaft.

3. In means of the character described, the combination of a valve, a rotatable shaft, operative connections between the said valve and shaft, a bearing for supporting the said shaft, which bearing is mounted upon a side of the said tank, the said shaft being provided with an upwardly and inwardly extending arm having an opening through its upper end portion, a rod extending from the outside of the said wall through an opening therethrough, said rod being supported by the said wall and extending through the opening in said arm, means for retaining the said rod in engagement with the said opening, and means whereby reciprocatory movement of the said rod may be effected to actuate the arm with which it is connected to thereby effect rotation of the said shaft.

4. In a device of the character described, the combination of a flush tank one wall of which is provided with an opening extending therethrough, an arm having an opening therethrough in alignment with the opening through the said wall, a bushing member extending through the said openings, means for retaining the said bushing and the said arm in position, the said arm being provided with a bearing in its outer end, a shaft mounted in said bearing, a valve, connections between the said valve and shaft, an arm extending upwardly and inwardly from the said shaft, said arm being provided with an opening through the upper end portion thereof, a rod slidably mounted in said bushing, the inner end of said rod extending through the opening through the said last mentioned arm, means for retaining the said rod in engagement with the said opening, and means whereby outward sliding movement of the said rod within the said bushing may be effected to open the said valve.

In testimony that I claim the foregoing as my invention, I have hereunto signed my name this 4th day of March, A. D., 1926.

WILLIAM U. GRIFFITHS.
